UNITED STATES PATENT OFFICE.

FRANCESCO FERRARA, OF BOSTON, MASSACHUSETTS.

SHOESTRING FASTENER.

1,072,594.

Specification of Letters Patent. Patented Sept. 9, 1913.

Application filed February 17, 1913. Serial No. 748,804.

To all whom it may concern:

Be it known that I, FRANCESCO FERRARA, a citizen of the United States, residing at Boston, in the county of Suffolk and State of Massachusetts, have invented new and useful Improvements in Shoestring Fasteners, of which the following is a specification.

This invention relates to improvements in shoe-string fasteners, the object being to provide a simple, inexpensive fastener which may be applied to any shoe having a tongue, said fastener being adapted to secure the ends of the shoe string by the mere winding of the ends of said string about said fastener, thus rendering unnecessary the use of knots.

The invention consists in the combination and arrangement of parts whereby the above objects and certain other objects hereinafter appearing are attained, as set forth in the following specification and particularly pointed out in the claims.

Referring to the drawings: Figure 1 is a front elevation of the upper portion of a shoe with a device embodying my invention attached to the tongue thereof. Fig. 2 is a vertical section, partly in elevation, taken on the line 2-2 of Fig. 1. Fig. 3 is a horizontal section, partly in elevation, taken on the line 3-3 of Fig. 1. Fig. 4 is a front elevation illustrating a modified form of the invention. Fig. 5 is a section, partly in elevation, taken on the line 5-5 of Fig. 4. Fig. 6 is a front elevation of still another modified form of the invention.

Like numerals refer to like parts throughout the several views of the drawings.

In the drawings, 8 is a shoe upper, which is partly broken away to save space in the drawings, and comprising lacing hooks 9 arranged in the usual manner and a shoe lacing 10 shown laced thereto.

11 is a tongue constituting a part of a shoe comprising the upper 8. To the upper end 45 of the tongue 11, substantially in alignment with the uppermost pair of lacing hooks 12 is a shoestring fastener 13, which is preferably though not necessarily detachably secured to the tongue 11 in a manner hereinbefore set forth. The fastener 13 comprises a base 14 which is preferably constructed of sheet material, while upon said base are arranged studs 15 comprising heads 16 and necks 17.

55 The preferred arrangement of the studs 15, with relation to the base 14, is as illus-

trated in Figs. 1 and 3, that is, with the center lines of said studs substantially parallel with each other and with said heads at but a slight distance apart, said distance 60 being wide enough to admit a shoestring therebetween.

The necks 17 are preferably very short only long enough to permit the shoestring to be wound or coiled thereabout once. Arranged between the studs 15 I have preferably provided a rib 18 which may, if desired, be formed integrally with the base as shown, said rib extending laterally midway of the space between said studs is adapted to engage the lacing as it is coiled around the neck 17 and thereby firmly wedge said lacing against the adjacent under edge of the head 16.

The base 14 is further provided with a 75 guide eye 19, which may, if desired, be formed as illustrated in Figs. 1, 2 and 3 integrally with said base and slightly rounded to present a smooth rounded surface to the shoe string 10, the ends of which are 80 led from the uppermost eyelets, when eyelets are used, or from the lacing hooks 12 as illustrated in Fig. 1, through said guide eye 19 and thence around the necks of the studs 15, one of said ends being coiled 85 around one of said studs and the other of said ends being coiled around the other of said studs. The loose ends thereof are permitted to hang loosely therefrom, as illustrated in Fig. 1.

As hereinbefore stated, the fastener 13 is adapted to be used on any shoe having a tongue and there are many methods which may be employed to attach said fasteners to said tongue in such a manner that they 95 may be put on or taken off as desired, or said fasteners may be secured by eyelets to permanently remain upon the shoe. The preferred method however of attaching the fastener 13 to the shoe is to provide at the 100 rear of the base 14 a tongue 20, which is preferably formed integrally with said base and is doubled back at 21, extending downwardly parallel with said base, see Fig. 2. The tongue 11 of the shoe is slit at 22 and 105 23 transversely thereof and the tongue 20 of said fastener is inserted from the front of said tongue through the slit 22 and along the rear of said tongue and thence through the slit 23 to the front thereof, said 110 tongue being held in engagement with said slits by the lacing.

In Fig. 4 I have illustrated another form of the invention which comprises a base 24 formed of sheet material and comprising a guide eye 25 upon the upper edge and 5 formed integrally therewith, while upon the lower edge of said base 24 is formed a tongue 26, said tongue being arranged at the rear of the base 24 a short distance therefrom and substantially parallel therewith. 10 The base in this form is preferably flat throughout its entire width, no rib being necessary in this case as the heads 27 of the studs 28 are connected to the base 24 by necks 29 which are oblique to the under 15 sides of said heads inclining inwardly toward the eye 25 and as the opposite ends of the lacing 30, as illustrated in dotted lines Figs. 4 and 5, are led through the guide eye 25 from opposite directions and 20 thence around the necks of their respective studs 28 in one complete coil, said lacing will be wedged into the acute angle 31 and firmly pressed against the under side of the head 27, thus pinching the free end of said 25 lacing to such an extent that it would be impossible to pull it out.

Fig. 6 illustrates still another form of my invention, and in this form a single spur 32 is formed upon the base 33 which constitutes a guide for the lacing as the ends 30 of said lacing are led from the uppermost hooks or eyelets to their respective studs.

Having thus described my invention, what I claim and desire by Letters Patent 35 to secure is:

1. As an article of manufacture, a shoestring fastener comprising a base, a pair of parallelly disposed studs, heads therefor, necks connecting said heads with said base 40 with said heads in close proximity to each other, and a guide arranged substantially intermediate said studs adapted to receive both of the ends of a shoestring and guide said ends toward their respective studs.

45 2. As an article of manufacture, a shoe-

string fastener comprising a base, a pair of parallelly disposed studs, heads therefor, necks connecting said heads to said base with said heads in close proximity to each other, a shoestring having opposite ends 50 thereof coiled about the necks of said studs respectively, and means located intermediate said studs adapted to pinch the coils of said shoestrings against the heads of said studs.

3. As an article of manufacture, a shoestring fastener comprising a base, a pair of parallelly disposed studs, heads for said studs, and necks connecting said heads with said base, in combination with a shoestring 60 having opposite ends thereof coiled about the necks of said studs respectively, a guide arranged substantially intermediate said studs adapted to receive both of the ends of said shoestring and direct said ends to their respective studs, and means formed between said studs from the material constituting said base adapted to pinch the coils of said shoestring against said heads.

4. As an article of manufacture, a shoestring fastener comprising a base, a pair of parallelly disposed studs, heads for said studs, and necks connecting said heads with said base, in combination with a shoestring 70 having opposite ends thereof coiled about 75 the necks of said studs respectively, a guide arranged substantially intermediate said studs adapted to receive both of the ends of said shoestring and direct said ends to their respective studs, and means arranged between said studs adapted to pinch the coils of said shoestrings against the under faces of said heads.

In testimony whereof I have hereunto set my hand in presence of two subscribing 85 witnesses.

FRANCESCO FERRARA.
